W. COLBORN

RAILROAD JOINT

Filed July 17, 1923

— FIG. 1.

— FIG. 2.

— FIG. 4.

— FIG. 5.

William Colborn

By *William J. Colborn*

Inventor

Attorney

UNITED STATES PATENT OFFICE.

WILLIAM COLBORN, OF FAIRMONT, WEST VIRGINIA.

RAILROAD JOINT.

Application filed July 17, 1923. Serial No. 652,081.

To all whom it may concern:

Be it known that I, WILLIAM COLBORN, a citizen of the United States, residing at Fairmont, in the county of Marion and State of West Virginia, have invented certain new and useful Improvements in Railroad Joints, of which the following is a specification.

This invention relates to a railroad joint and has for its principal object to provide a simple and efficient device which is adapted for use in connection with mine rails and which will provide an efficient joint between the ends of abutting rails whereby the same are held in proper alignment.

Another important object of the invention is to provide a railroad joint of the above mentioned character which may be easily and quickly placed in position for the purposes above set forth and does not require the use of additional fastening means such as bolts or the like in order to hold the same in proper position thereon.

Another important object of the invention is to provide a railroad joint of the above mentioned character which is simple in construction, inexpensive, strong and durable, and well adapted for the purposes for which it is designated.

Other objects and advantages of this invention will become apparent during the course of the following description.

In the accompanying drawings forming a part of the specification, and in which like numerals designate like parts throughout the same,

Figure 1 is a top plan view showing my railroad joint in position on a pair of abutting rails.

Figure 2 is a bottom plan view thereof,

Figure 3 is a transverse section taken on line 3—3 of Fig. 1 and looking in the direction of the arrows,

Figure 4 is a perspective view of one of the clamping plates.

In the drawings wherein for the purpose of illustration is shown the preferred embodiment of my invention, the numeral 1 designates the clamping member formed of suitable sheet metal material and comprises a base plate 2 which is adapted to be placed against the bottom of the abutting rails A and B respectively. The clamping member 1 furthermore includes an upstanding portion 3 which is adapted to extend over the base flanges C and D respectively then

bent upwardly to fit against the web portion of the rails as more clearly shown in Fig. 3 of the drawings.

This clamping member 1 is adapted to have its base plate 2 terminate at a point adjacent the opposite longitudinal edge of the base flanges of the abutting rails for the purpose to be hereinafter more fully described. The clamping member 1 has its extension 3 furthermore provided with a series of spaced slots 4 therein adjacent the base plate 2 as more clearly shown in Fig. 4 of the drawings, and adapted to be received in these spaced slots 4 are the transversely extending strips 5.

Each of these transverse strips 5 is formed of a material similar to the material used in the construction of the clamping member 1 and has one end thereof bent around to engage the base flange of the rails as shown at 6 in the drawings and the opposite end of each strip is adapted to extend around the rail bottoms and also the bottom of the base plate 2 of the clamping member 1, and the free end of each strip is passed through a respective slot provided in the extension 3 so as to cause the free end of each strip to be disposed between the bottom of the rails and the top face of the base plate 2 in the manner more clearly illustrated in the Fig. 3 of the drawings.

Any number of these transverse strips 5 may be associated with the clamping members 1 in accordance with the provisions of the slots 4 formed in the clamping plate.

It is to be understood in assembling the device, the inner ends of the strips 5 are first placed through the slots 4 so as to lie between the rail bottoms and the upper face of the base plate 2, and the opposite ends are bent around the bottom of the base plate 2 and thence bent upwardly to engage the base flanges of the rails. The hook ends 6 of the strip 5 are then swaged down on the rail base after being placed under the rails.

In this manner the transverse strips 5 are securely held in position upon the base plate 2 and also their base flange engaging portions 6 will securely hold the abutting rails in proper alignment and will prevent the ends of the rails from moving sidewise. Furthermore the simplicity of my rail joint enables the same to be easily and quickly placed in position upon the

ends of a pair of abutting rails and does not require the use of bolts or spikes which are now commonly used in securing a rail joint in position on the railroad tie.

From the foregoing description of the construction of my improved apparatus, it will be seen that I have provided a simple, inexpensive and efficient means for carrying out the objects of the invention, and while I have particularly described the elements best adapted to perform the functions set forth, it is obvious that various changes in form, proportion, and in the minor details of construction may be resorted to, without departing from the spirit or sacrificing any of the principles of the invention.

I claim:

A rail joint of the class described comprising a clamping member including a base plate having one longitudinal side provided with an extension adapted to extend over one side of the base flanges of a pair of abutting rails and fitting against the web portions thereof, a series of transverse strips each having one end in engagement with the opposite side of the base flanges of said abutting rails, the other end of each strip extending through a slot provided in said clamping member adjacent the base plate thereof and disposed between said base plate and the bottom of said rails.

In testimony whereof I affix my signature.

WILLIAM COLBORN.
